ATTORNEY

UNITED STATES PATENT OFFICE.

GEORGE HUDSON, OF MARINETTE, WISCONSIN.

ATTACHMENT FOR WINDOWS.

Application filed March 4, 1922. Serial No. 541,141.

To all whom it may concern:

Be it known that I, GEORGE HUDSON, a citizen of the United States, residing at Marinette, in the county of Marinette and State of Wisconsin, have invented new and useful Improvements in Attachments for Windows, of which the following is a specification.

This invention comprehends the provision of a window support designed to be positioned in the guideway of the window sash, to support the latter in any desired opened position and conveniently removed when it is desired to close the window.

In carrying out the invention, I employ a cam-like member which has associated therewith means for engaging said frame so that the support in its entirety can be conveniently arranged at any particular location on the window frame beneath the window sash to support the latter in an opened position, the cam-like member being pivoted on the frame engaging means so as to bind or impinge between the parting strip and the window frame to support the window.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1 is a view of supporting the window in accordance with the present invention.

Figure 2 is a sectional view taken on line 2-2 of Figure 1.

Figure 3 is a perspective view of the invention.

Figure 4 is an edge elevation.

Referring to the drawing in detail, A indicates the window frame, B the window sash, and C the parting strip.

The support forming the subject matter of the present invention comprises a cam-shaped element 10 designed to be positioned in the guideway for the window sash, and adapted to engage the parting strip C and the opposed portion of the window casing in a manner to support the window sash in an opened position. This cam-shaped ele-

ment has associated therewith a member designed to engage and slide upon the window casing, the cam-shaped element being pivoted upon the member indicated at 11. This member 11 terminates at one end to provide a hook-like portion 12 which is adapted to engage the window casing in a manner illustrated in Figures 1 and 2, while the opposite end of the member is offset as at 13, constituting a pivot for the cam-shaped element 10 through which it is passed. Also projecting from one side of the cam-shaped element 10 is a handle 14 by means of which the device in its entirety can be conveniently handled.

In practice, the window is opened, and the cam-shaped element arranged in the guideway as illustrated in Figures 1 and 2 with the hook-like extremity of the member 11 engaging the window casing. By grasping the handle 14, the device in its entirety can be moved in the guideway to any desired position, and subsequently, the cam-shaped element moved about its pivot in a direction to cause it to engage the parting strip C in the window casing A. In this manner, the cam-shaped element is held immovable within the guideway to support the window which reposes upon the cam-shaped element as shown, the weight of the window causing the cam-shaped element to more effectively grip or engage the window casing and parting strip for the purpose stated. The device in its entirety is very simple in construction, and can be manufactured and sold at a very nominal cost.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A window support comprising a cam-shaped element adapted to be arranged in the guideway of the window, a hook-like member associated with said element and adapted to slidably engage the parting strip, one terminal of said member being offset and constituting a pivot for said cam-shaped element, and a handle projecting from said element for the purpose specified.

2. A window support comprising a cam shaped element adapted to be positioned in the guideway for the window sash in engagement with the parting strip, and a substantially U-shaped clamp adapted to embrace said parting strip to support said cam shaped element in position for use, one limb of said clamp constituting a pivot on which the cam shaped element is mounted, said

clamp being susceptible of vertical adjustment along the parting strip so that the window can be supported in any adjusted position, and a handle projecting from the cam shaped element whereby the latter can be conveniently manipulated.

15 In testimony whereof I affix my signature.

GEORGE HUDSON.
